(57) **CLAIM**

The ornamental design for a telescopic stool, as shown and described.

DESCRIPTION

FIG. 1 is a top, front perspective view of a telescopic stool, showing our design.

FIG. 2 is a bottom, rear perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof.

FIG. 9 is a top, front perspective view thereof, shown in a folded status.

FIG. 10 is an enlarged view of the area labeled 10 in FIG. 1.

FIG. 11 is an enlarged view of the area labeled 11 in FIG. 2; and,

FIG. 12 is an enlarged view of the area labeled 12 in FIG. 3.

The broken lines in the drawings depict details and features of the telescopic stool that form no part of the claimed design.
